United States Patent Office.

H. SCHEVENELL AND S. S. REMBERT, OF NEAR MEMPHIS, TENNESSEE.

Letters Patent No. 77,539, dated May 5, 1868.

INSTRUMENT FOR TREATING PILES.

The Schedule referred to in these Letters Patent and making part of the same.

TO ALL WHOM IT MAY CONCERN:

Be it known that we, H. SCHEVENELL and S. S. REMBERT, of near Memphis, in the county of Shelby, and State of Tennessee, have invented a new and improved Instrument for Treating Hemorrhoids or Piles; and we do hereby declare that the following is a full, clear, and exact description thereof, which will enable those skilled in the art to make and use the same, reference being had to the accompanying drawings, forming part of this specification, in which—

The drawing represents a perspective view of our improved instrument.

The nature of our invention relates to the treatment of the inflammation of the anus and rectum, commonly known as hemorrhoids or piles.

The principle of its action consists in the employment of a galvanic pole or electrode, composed of a combination of different metals which are most productive of galvanic action. The galvanic action induced by the contact of the metals and the moisture of the parts with which they are in contact conduces to reduce the tumid and inflamed state of the parts.

It is well known that two or more metals, placed in contact with each other and with moisture, will institute a galvanic action, or, more properly, an electric current of feeble tension.

The employment of electricity in the treatment of disease, by topical application of the current, is generally recognized as an effective means of treatment in certain pathological conditions, and our invention provides a readily available means of applying electricity to the diseased part, as will hereinafter be more fully set forth.

The electrode is composed of any suitable metals, as zinc and silver, or zinc and copper, or zinc and platinum, or other permutations of these or other metals.

The form of the instrument is shown in the drawing, A being the part for insertion, and B the base or body, to insure a more positive galvanic action due to a larger bulk of metal.

The pressure of the part A upon the tumors, and the low temperature of the metal, will also exert a curative effect, compressing and contracting the tumid parts, while the galvanic current will impart tone and induce the normal circulation, the previous interruption of which constitutes, *per se*, the inflamed condition familiarly known as piles.

The base, B, may be made hollow, to admit any solution, as that of sulphate of copper, and the metals composing the part A so combined in contact as to produce the galvanic action in a greater degree.

The cavity in the base, being closed by means of any suitable screw-cap, the instrument could be conveniently applied without connecting it with a common battery.

The instrument is also available for the application of cold, as the temperature of the same may be lowered by any of the common frigorific mixtures, as salt and ice, or the admixture of certain chemical salts, and the combined effect of the galvanic current with the reduced temperature will conduce to remove the inflammation.

The cavity in the base may be covered with a cap of rubber, and the water contained in the cavity frozen by frigorific mixtures, as aforesaid, and the reduced temperature thus retained for a longer time.

In the figure, the vertical strips of copper or other metal are shown at *a a*, while the other part, *b*, in which it is embedded, is of zinc or other different metal.

The electrode may be made with a suitable form for treating the vagina or uterus, and may be made sufficiently light to be worn in position for several hours, being provided with any suitable straps for retaining it in place.

We claim as new, and desire to secure by Letters Patent—

The electrode A B, composed of different metals *a a b*, substantially as shown and described, for the purpose set forth.

H. SCHEVENELL,
S. S. REMBERT.
